INVENTOES:

INVENTORS:

UNITED STATES PATENT OFFICE.

JOHN HOPE AND JOHN HOPE, JR., OF PROVIDENCE, RHODE ISLAND, ASSIGNEES TO THE JOHN HOPE & SONS' ENGRAVING AND MANUFACTURING COMPANY, OF SAME PLACE.

BAR-SUPPORT FOR PANTOGRAPH ENGRAVING-MACHINES.

SPECIFICATION forming part of Letters Patent No. 665,098, dated January 1, 1901.

Application filed August 21, 1899. Serial No. 727,877. (No model.)

To all whom it may concern:

Be it known that we, JOHN HOPE and JOHN HOPE, Jr., of Providence, in the county of Providence and State of Rhode Island, have 5 invented a new and useful Improvement in Bar-Supports for Pantograph Engraving-Machines; and we hereby declare that the following is a full, clear, and exact description of the same, reference being had to the accompanying drawings, forming part of this specification.

In pantograph engraving-machines the movement of the stylus in tracing the pattern is transmitted to the gravers and to the roll by means of bars engaging with levers or carriages connected with the gravers or the work. It is important that these connections are flexible, so as to readily move with the movement of the stylus and with the least possible resistance, and these connections must be so positive that the slightest movement of the stylus will be transmitted.

The invention consists in the peculiar and novel construction by which the bar or lever 15 is supported on the beveled edges of two disks journaled on antifriction-bearings in a block, as will be more fully set forth hereinafter.

Figure 1 is a front view of the support. Fig. 2 is a side view of the same. Fig. 3 is a 25 plan view of the supporting-block, the beveled disks being shown in broken lines. Fig. 4 is a sectional view of the supporting-block, showing the ball-bearings of the spindle supporting the block. Fig. 5 is a sectional view 35 of the block, showing the bearing of the spindle of one of the beveled disks.

In the drawings, *a* indicates the part of a pantograph engraving-machine from which motion is transmitted to another part of the 40 machine, usually an arm on which the block is pivotally supported; *a'*, the spindle, secured to the arm *a*, preferably by a clamp-screw, as is shown in Figs. 1 and 2, forming the pivotal support of the block; *b*, the supporting-block; *b'*, the bearings for the spindle *a'*, and *b'* the bearings for the spindles *c'* of the beveled disks *c c*. The spindles *a'* and *c'* are provided with the annular grooves *a²* *a²* and *c²* *c²* for the balls. The bearings *b'* and *b'* 45 are made up of the races *b³* *b³*, adjustably held in the required position above and below each

of the ball-bearings *b⁵* by the lock-nuts *b⁴* *b⁴* in screw-thread engagement with the internally-screw-threaded holes *a³* in the block *b*. Portions of the block *b* are cut away at *b⁶* *b⁶* 55 to give access to the several lock-nuts *b⁴* to permit of their adjustment by means of a pin which enters holes in the peripheral surface of the lock-nuts *b⁴*. The bar *d* may be the bar connected with the stylus-carriage or any other bar of the pantograph engraving-machine by which or through which motion is transmitted. The bar *d* bears on the adjacent inclined edges of the beveled disks *c c* and may be moved longitudinally, thereby 65 causing the beveled disks to rotate, or the bar *d* may be moved laterally to move the arm *a* laterally, or when the bar *d* and the arm *a* are pivotally supported the arm *a* may impart a swinging movement to the bar *d*, or 70 vice versa. By this construction the bar *d* is firmly supported on the adjacent beveled edges of the disks *c c* and may be moved longitudinally practically without any frictional resistance, while the disks freely adjust themselves to the bar automatically by the swinging 75 of the block *b*.

Having thus described our invention, we claim as new and desire to secure by Letters Patent—

1. In a bar-support for pantograph engraving-machines, in combination, a block supported on a spindle, two disks having beveled edges, a spindle secured to each of the two disks extending downwardly therefrom and 85 pivotally supported in the block; whereby a bar may be supported on the beveled edges of the disks, as described.

2. In a bar-support for pantograph engraving-machines, the combination with a member of the machine, and a spindle carried by the member, of a block pivotally supported on the spindle by ball-bearings, two disks having beveled edges, spindles on the disks journaled on ball-bearings in the block, and means for adjusting the ball-bearings; whereby motion may be transmitted from one part of the machine to another part in one direction while part of the machine is free to move with or on the beveled disks.

3. In a bar-support for pantograph engraving-machines, the combination with the spin-

dle a' secured to one part of the machine, the block b , the beveled disks $c c$ and the spindles $c' c'$, of annular grooves on the spindles for the balls $b^5 b^5$, the races $b^3 b^3$ above and 5 below each series of balls, the lock-nuts $b^4 b^4$ in screw-thread engagement with the internally-screw-threaded holes $a^3 a^3$, the holes in the peripheral surfaces of the lock-nuts, and the cut-away portions $b^6 b^6$; whereby the ball- 10 bearings for the spindles may be adjusted and

the support may automatically adjust itself, as described.

In witness whereof we have hereunto set our hands.

JOHN HOPE.
